UNITED STATES PATENT OFFICE.

PHILIP A. KOEHRING, OF MILWAUKEE, WISCONSIN, ASSIGNOR TO KOEHRING MACHINE COMPANY, OF MILWAUKEE, WISCONSIN, A CORPORATION OF WISCONSIN.

CONVEYER APPARATUS.

1,227,157.

Specification of Letters Patent. Patented May 22, 1917.

Application filed October 6, 1914. Serial No. 865,335.

To all whom it may concern:

Be it known that I, PHILIP A. KOEHRING, a citizen of the United States, residing at Milwaukee, in the county of Milwaukee and State of Wisconsin, have invented certain new and useful Improvements in Conveyer Apparatus, of which the following is a specification.

In my Letters Patent, reissued September 16, 1913, Number 13,617, is described improved conveyer means in the form of a concrete distributor especially designed for use in delivering mixed concrete from a mixer to a suitable point of deposit. The machine of the above Letters Patent has been found of unusual practical value in quickly and economically effecting a distribution of materials over a suitable area. It is an especial object of my present invention to provide a conveyer mechanism adapted to be used in connection with the distributing means of the above patent whereby instead of requiring the manual loading of the concrete mixer as by depositing wheel barrow after wheel barrow in a loading bucket adapted to dump into such mixer, I am enabled to employ mechanical means solely, such as a grab bucket and suitable controlling mechanism, whereby to effect the loading operation above referred to. The conveyer mechanism of the present invention while especially intended for association with concrete mixers may, of course, be employed in many other ways in which conveyers are generally utilized.

Among the objects in view in respect to the particular improvements hereinafter set forth in detail are the effective handling and delivery of concrete materials by mechanism characterized by ease and simplicity of control; the provision for stability of the supporting part and the relative disposition of parts for insuring economical co-operation.

With these and other objects in view, as will in part hereinafter become apparent and in part be stated, the invention comprises a framework, a mixing drum sustained thereby, a boom movably carried by the framework, a load conveying carriage movably mounted on the boom, means for shifting the carriage, and means for delivering the load conveyed by the carriage to the mixing drum.

The invention further comprises a frame-

work, a boom pivotally carried thereby and having a trackway, a brace sustaining the free end of the boom and pivoted coaxially with the boom, and a load carrier movable along the boom past the brace, the brace comprising a single member at its lower portion and being bifurcated at its upper portion for allowing the passage of the load carrier.

The invention comprises certain other novel constructions, combinations, and arrangements of parts as will be hereinafter fully described and claimed.

In the accompanying drawing:

Figure 1 is a view in side elevation of an apparatus embodying the features of the present invention, intermediate parts being broken away.

Fig. 2 is a top plan view thereof, portions of the gearing and lower operating parts being omitted.

Fig. 3 is a rear end elevation thereof.

Fig. 4 is a diagrammatic showing of the controlling and actuating cables.

Fig. 5 is a detail view of a link used.

Referring to the drawing by numerals, 1 indicates a truck frame sustained by wheels 2, 2 and supporting a superstructure framework 3. Journaled in brackets sustained by the frame 1 are rollers 4, 4 which rotatably support a mixing drum 5. An engine 6 is sustained by the frame 1 and may be of the internal combustion type or may be a steam engine supplied with steam from boiler 7 also sustained by the frame 1. Engine 6 is geared to drive a main drive shaft 8 which extends substantially throughout the length of frame 1 and is provided with gears 9 meshing with gears 10 formed on the periphery of drum 5. Appropriate controlling clutch and transmission gear mechanism are adapted to deliver power from shaft 8 to the rear wheels 2 for causing the structure to act as a tractor for purposes of transportation.

Fixed in the framework 3 above drum 5 is a platform 11 facilitating access by an operator to various parts of the apparatus. A hopper 12 is fixed in the framework 3 in advance of the platform 11 and is formed with a chute 13 discharging into drum 5. Hoppers 14, 14 are arranged above hopper 12 and sustained in the framework, each of the hoppers 14 being provided with a discharge chute 15 controlled by a gate 16.

and disposed to direct the discharge into the hopper 12, the two gates 16 being fixed to an actuating shaft 17 for being manually operated.

5 In the uppermost portion of the framework 3 a boom 18 is journaled and is provided with an extended terminal portion 19 formed with a horizontally arranged and arcuate rack 20 with which meshes the bevelled gear 21 carried by shaft 22 journaled in bearings 6' fixed to frame 3. The rear end of shaft 22 carries a bevel gear 23 meshing with a similar gear 24 fixed to a vertically disposed shaft 25. The lower portion 15 of shaft 25 extends past shaft 8 and carries oppositely disposed bevel gears 27 and 28 loosely mounted on the shaft and adapted to be connected therewith alternately by a clutch member 29 slidingly 20 mounted on shaft 25 and disposed to engage co-operating clutch teeth on the contiguous faces of gears 27, 28. A bevel gear 30 is fixed to shaft 8 and meshes with gears 27, 28, so that when clutch 29 engages gear 28 boom 18 will be swung in one direction, and when the clutch engages gear 27 the boom will be swung in the opposite direction. Boom 18 consists of a pair of parallel beams fixed together at their inner ends by being 30 bolted to or otherwise connected with an interposed block having the rear extension 19, and said beams extend forwardly to the outer end of the boom where they are connected by a cross beam, preferably a channel plate 31. Plate 31 extends laterally beyond the beams comprising boom 18 and at each of its ends is engaged by a beam 32, the beams 32 extending parallel to each other and inclined downwardly and rearwardly to a cross channel plate 33 which is 40 fixed to the lower end of the beams 32 at its ends, and at its center being fixed to a beam 34 which extends at the same angle as beams 32 down to a point in axial alignment with the pivot of boom 18, at which point the beam 34 is pivotally sustained in the frame 3, so as to swing with the boom, the said beam 34 and beams 32 comprising an inclined brace for the boom. 45 A carriage 35 is provided with flanged wheels engaging the beams of boom 18 and is adapted to travel longitudinally of the boom. An ordinary grab bucket 36 is arranged to be sustained by, to depend from 50 and to travel with the carriage 35, the bifurcation of the inclined brace permitting the grab bucket to pass through the brace during travel along the beam. The shells or scoops comprising the bucket proper of the 55 grab are closed by the usual pulley carrying levers and cable interlaced therethrough, the pivotal movement of the scoops being effected on divergent brace rods sustained by the casing 37 of the uppermost pulley. Upstanding from the casing 37 are ears 38 through which is extended a pin 39 engaging a link 40, the latter extending upwardly into position for engaging hooks 41 carried by operating levers 42 pivoted to the body of carriage 35. Springs 43 engage the upper portions of the levers 42 for normally maintaining the hooks in engagement with link 40. The link 40 is preferably constructed in the form of a T with the head of the T arranged horizontally to engage hooks 41 75 and its body pendent. The upper end portions of levers 42 are connected by cross pin 44 which is engaged by a cable 45 extending from the cross pin forwardly along the boom 18 to and about a pulley 46 journaled at the free end of the boom 18. Cable 45 extends thence rearwardly along the boom 18 and is passed about a guiding pulley 47, about pulley 48 and downwardly about a pulley 49 journaled on shaft 8, and thence upwardly 80 about a pulley 50 and about a pulley 51 to the cross pin 44. Thus the carriage 35 is free to ride along the boom while the levers 42 remain in their bucket supporting position, the cable 45 merely shifting longitudinally to an extent responsive to movements of the carriage. It will of course be obvious, however, that an appropriate pull on cable 45 will swing levers 42 on their pivots and thus move hooks 41 out of engagement with link 40, releasing the bucket and allowing it to drop or open according to the paying out of the bucket supporting cable hereinafter described. The pull on cable 45 may be effected in any of various 90 ways, as manually, or, when the carriage is moving inwardly, by the use of a brake applied to pulley 49 for stopping the longitudinal travel of cable 45 while the carriage 35 continues to move which will give the 95 effect of a pull on the cable since the pivot of levers 42 is moved relative to the point of engagement 44 of cable 45. The controlling pulleys of the bucket 36 have a cable 52 laced therethrough, one end 100 of the cable being connected to a fixed part of carriage 35 and the other portion of the cable beyond the pulleys of the bucket extending past guiding pulleys 53, 54 and 55 and thence downwardly to winding drum 56 115 mounted on shaft 8 and adapted to be driven thereby through a clutch 57. A friction brake 58, preferably of the band type, engages a portion of the drum 56 for controlling rotation thereof. A cable 59 is fixed 120 to carriage 35 and extends outwardly along the boom 18 to and about an idler pulley 60, and extends thence rearwardly along the boom to and about guiding pulleys 61 and 62 and thence downwardly to an operating 125 drum 63. Drum 63 is carried by shaft 8 and is adapted to receive power therefrom through a clutch 64. Pulleys 46 and 60 are journaled on a shaft upstanding from the outer end por- 130

tion of boom 18 and common to the pulleys, the pulleys being mounted to rotate about a vertical axis. Pulleys 48, 50, 55 and 62 are journaled in appropriate brackets fixed 5 to the frame 3, the pulleys being mounted to rotate about horizontal axes and each located relative to the particular element below to which the respective engaging cable extends. Pulleys 47, 51, 61 and 54 are 10 mounted to rotate about a vertical axis, being all journaled on a common supporting shaft carried by the arms of the bifurcated bracket 65, seen best in Fig. 3, which is fixed to frame 3 and positioned for maintaining the several pulleys last named in 15 the proper relation to the boom 18. A guy strip 66 is fixed to the upper arm of bracket 65 and extends on an incline rearwardly and is fixed to frame 3 for aiding in resisting stresses longitudinal of the boom 18.

A discharge chute 67 extends rearwardly from within drum 5 to a delivery chute 68 for delivering the mixed concrete either to the point of consumption or to a conveyer. 20

In operation, the parts being in the position indicated in Fig. 1 and clutch 57 being open, clutch 64 is closed for actuating the drum 63 and thus exerting a pull on the carriage 35 which causes the carriage to 25 be drawn outwardly along boom 8, this movement continuing until the carriage either arrives at the outer end of the boom or above the point of deposit of the material to be delivered to hopper 14. Upon 30 reaching this point the cable 45 is given a pull for swinging the levers 42 to the bucket releasing position, the carriage at the same time being stopped by opening clutch 64. Brake band 58 is of course released during 35 the outward travel of carriage 35 and being left open, cable 52 continues to feed outwardly as the bucket 35 descends under its own weight. When the bucket has reached the supply of material and the scoops have 40 engaged a portion thereof sufficient for constituting a load, the clutch 57 is closed and the drum 56 thus driven for reefing in the cable 52 whereby the bucket is closed in the usual manner and then drawn upwardly 45 until link 40 passes the beveled under surfaces of hooks 41 and has its head resting upon the hooks. The carriage 35 is provided with pendent sheets or plates between the beams of boom 18, each plate being 50 notched as indicated at 35' for the reception of the head of link 40 and the edges of the plates are beveled to guide the head into the notch for insuring engagement of the head with the hooks and for maintaining such engagement. As soon as the bucket has 55 reached this position the continued reefing in of cable 52 causes the carriage 35 to be drawn inwardly along the boom 18 until the bucket arrives at a point above hoppers 14 whereupon the band brake 58 is set and the clutch 57 released. This holds the parts in inoperative position with the bucket suspended above the hoppers. When the hopper is ready to receive the charge from the bucket, band brake 58 is released and the 60 bucket allowed to automatically dump its load into hoppers 14. Gates 16 are opened by actuation of an appropriate lever 17' connected with shaft 17, see Fig. 3, for allowing a charge to be delivered to the 65 hopper 12, all, or any appropriate portion of the load delivered to the hopper being permitted to pass through chutes 15 before the gates 16 are closed. A gate 13' is preferably provided for chute 13 and suitable 70 means not forming any part of this invention are provided so that the charge admitted to the hopper 12 can be delivered to the drum 5 at an appropriate moment consistent with conditions within the drum 75 at the will of the operator. When further loads are to be delivered by the bucket, the operation is repeated. In the course of use, different materials will naturally be deposited at different points laterally of the machine and to enable the requisite lateral movement of bucket 35 for causing the bucket to approach the particular point of supply, the shaft 22 is actuated for swinging boom 18 angularly to the required position. 80

Having thus described the invention, what is claimed is:—

1. In a conveyer, the combination with a framework, of a boom pivotally mounted therein, a carriage movable along the boom, a grab bucket releasably sustained by the carriage, cables for shifting the carriage and for actuating the grab bucket, a cable for controlling the carriage sustaining means for the grab bucket, a shaft common to all of said cables, means for operating the same, and cable control means associated with the shaft. 90
2. In a conveyer, the combination with a framework, of a boom pivotally mounted therein, a carriage movable along the boom, a grab bucket releasably sustained by the carriage, cables for shifting the carriage and for actuating the grab bucket, a cable for controlling the carriage sustaining means for the grab bucket, a shaft common to the cables and the boom, means for operating the same, control means carried by the shaft for controlling said cables, and means actuated by the shaft for swinging the boom on its pivot. 100
3. In a conveyer, the combination with a framework, and a boom pivotally mounted therein of a carriage shiftable along the boom, a grab bucket adapted to be detachably sustained by the carriage; a cable for shifting the carriage outwardly along the boom fixed to the carriage and extending to the outer portion of the boom and having 110

- 22
- a return portion, a pulley journaled at the outer portion of the boom and engaged by said cable, cable guiding pulleys for the return portion of said cable for directing the 5 same downwardly into the framework, a grab bucket actuating and carriage return cable connected to said carriage and engaging the grab bucket for actuating the same and extending inwardly from the carriage, 10 a guiding pulley on the carriage for the last named cable, guiding pulleys sustained by the framework for the last named cable for directing the same downwardly in the framework, releasing means for the grab 15 bucket sustaining means, a cable for controlling and actuating said releasing means engaging the same substantially at the carriage and extending outwardly to the outer portion of the boom and having a return 20 portion, a pulley journaled at the outer portion of the boom for guiding the cable of the releasing means, the said return portion of the cable extending inwardly substantially to the inner end of the boom and 25 thence downwardly into the framework and again upwardly to the boom and outwardly to the releasing means, pulleys guiding the portions of said cable, and means for actuating and controlling all of said cables. 30 4. In a conveyer, the combination with a framework and a boom pivotally mounted therein, of a carriage shiftable along the boom, a grab bucket adapted to be releasably sustained by the carriage, cables for controlling the grab bucket and shifting the carriage, a cable for controlling and actuating the sustaining means for the grab bucket, 35 pulleys for guiding said cables, some of said pulleys being arranged in a superposed series at the inner end portion of the boom, a bifurcated bracket fixed to the framework laterally of the boom and having said superposed pulleys journaled in the bracket between the arms of the bifurcation, and 40 means for controlling and actuating said cables. 5. In a conveyer, the combination with a framework and a boom pivotally mounted therein, of a carriage shiftable along the 45 boom, a grab bucket adapted to be releasably sustained by the carriage, cables for controlling the grab bucket and shifting the carriage, a cable for controlling and actuating the sustaining means for the grab
- bucket, pulleys for guiding said cables, some 55 of said pulleys being arranged in a superposed series at the inner end portion of the boom, a bifurcated bracket fixed to the framework laterally of the boom and having said superposed pulleys journaled in the 60 bracket between the arms of the bifurcation, a guy fixed to the bracket substantially in the rear and approximately alined with the boom and extending to and engaging the framework, and means for controlling and 65 actuating said cable. 6. In a conveyer, a boom, a carriage arranged to traverse the boom, a bucket movably supported by the carriage, lock means to hold the bucket in a predetermined position in respect to the carriage, cable means to operate the carriage and to move the bucket thereon into coöperation with the lock means, cable means to control operation of the lock means, whereby to lock the carriage or release the same for movement relative to the carriage, and a main operating device connected with the carriage operating cable means and coacting with other cable means aforesaid to cause bucket release operation. 7. In a conveyer, a boom, a carriage arranged to traverse the boom, a bucket movably supported by the carriage, lock means to hold the bucket in a predetermined position in respect to the carriage comprising a release lever having a hook to engage and hold the bucket in a charged position, cable means to operate the carriage and to move the bucket thereon into coöperation with the lock means, cable means to control operation of the lock means, whereby to lock the carriage or release the same for movement relative to the carriage, a main operating device connected with the carriage operating cable means and coacting with other cable means aforesaid to cause bucket release operation incidental to disengagement of the bucket from said release lever hook, and spring means normally tending to engage the hook with the bucket. 85 90 95 100
